UNITED STATES PATENT OFFICE.

FRED VAN WAY, OF COVINA, CALIFORNIA.

AUTOMATIC RAILWAY-CROSSING SIGNAL.

Application filed May 25, 1922. Serial No. 563,465.

This invention relates to that class of signals installed at points where roadways cross railways and operable by railway cars or trains for the purpose of preventing accidents caused by roadway vehicles attempting to cross the railway when the same should be kept clear for oncoming cars or trains, and is applicable to either trolley lines or steam railways where roadways cross the same.

10 An object of the invention is to provide a more positive and practical signal to warn the driver of an automobile or other road vehicle of the approach of a car or train on the railway.

15 The invention is broadly new, basic and pioneer in that I provide a horizontally swinging pendant-carrying arm and means operable by the car or train upon the railway track to swing said arm through a quadrant. An advantage of this novel construction is that it is thus made possible to quickly clear the road so that the vehicle stopped by the signal may proceed more expeditiously after the car on the railway has passed.

20 25 An object of the invention is to provide a warning signal of this character the control of which may be either automatic or manual so that the roadway may be opened or closed to traffic during switching operations on the railway.

An object of the invention is to provide a practical protection for road passengers against moving onto the track from either side of the railway and on either side of the roadway, and to effect this with a high degree of simplicity.

30 35 This invention is applicable independently of, and also in conjunction with, the usual wig-wag and bell signals common to railways at roadway crossings in different parts of the United States.

An object is to provide a positive warning to drivers of vehicles on roadways at a sufficient distance from the railway crossing to permit the stopping of said vehicles before the railway crossing is reached. And to provide warning to said vehicles without danger to either vehicle or signaling apparatus in the event that said vehicle should come in contact with the signaling apparatus.

40 Other objects, advantages and features of invention may appear from the accompanying drawings, the subjoined detail description and the appended claims.

45 50 The accompanying drawings illustrate the invention.

Figure 1 is a perspective view of my signal apparatus installed and in signaling position at a railway and roadway crossing.

Fig. 2 is a fragmental view showing in one scale, a plan of the signal apparatus installed at a road and railway crossing, and in a larger scale, a diagram of the electrical operating and controlling mechanism. The signals are shown in normal open road position. The signaling arms are indicated by the characters 1, 1', 1'', and 1'''.

Fig. 3 is a fragmental elevation partly in section of the apparatus in road closing position.

Fig. 4 is a fragmental detail showing the motor and electrical operating mechanism.

In Fig. 1, four horizontally swinging signaling arms 1, 1', 1'', 1''', are shown, each mounted on its vertical shaft 2, suitably journaled to revolve on a vertical axis; and said arms are provided with pendants 3 that may be of any suitable construction such as flexible strips of rubberized fabric adapted to hang down into the way of road passengers.

Each arm is fixed to its shaft 2 above the top of a hollow column 4 that forms a support for the bearings 5 of the shaft. Each shaft is provided at its lower end with means, as the miter gear 6 adapted to be rotated a quarter turn by suitable means, as the miter gear 12 that is driven by a reversible electric motor 8 which is operated by a suitable current from an approved source and may be operated by a circuit carried by wires along the track. Said motor is connected through reduction gears 34, shaft 10', and gears 9' and 9, to a shaft 10 extending across and under the railway A and provided with bevel gears 12 and 12', respectively, meshed with corresponding gears 7 and 13 that drive shafts 14 and 14' extending across and under the roadway B, and respectively provided with bevel gears 15 and 15' meshing with gears 16, 16' that revolve upright shafts 100 2' and 2 to swing the arms 1' and 1, positively, first in one direction a definite distance to a stop; and, upon reversal of the motor, a like distance in the other direction, to a stop, according to the motor operation.

Referring to Figs. 1 and 2, 17 and 18 indicate the rails of an insulated block A' of the railway track which is separated from the main track 19 by insulations 20 and 20'. The rails 17 on one side of the track are connected by a lead 21 to one pole of an electromagnet 22, and the rail 18 on the other side

of the track is connected by lead 23 with the other pole of the magnet 22.

- These connections are applied in the usual manner at one end of the block A of the railway, and at the opposite end of the block A, rail 17 is connected by lead 24 to one pole of the magnet operating battery 25. Rail 18 is connected by lead 26 to the other pole of battery 25. The electro-magnet 22 is normally energized from the battery 25, and when it is energized as shown in Fig. 2, the armature 27 is drawn toward the magnet 22 to close the circuit between the switch points 28 and 29, and between leads 30 and 31 of the motor operating circuit which is alternately connected through opposite sides of the switch 33 to the motor 8, for alternate operation of the motor in opposite directions.
- Electric switch 33 opens and closes the circuit between the contacts 32, 32', at the gap a, through the motor connection 31', to the motor 8. Said switch 33 is connected by reduction gear 34 to the motor 8 so that when the circuit is closed between switch points 28 and 29, and the gaps a, b, and c, of the switch 33, are closed, the motor will be driven in the direction of the unfeathered arrow for a sufficient number of revolutions to open the switch 33 at the gaps a, b, and c, and to close the circuits at the gaps d, e, and f. The wiring is such that when the gaps a, b, c are closed, and the switch 27' is in position to close the motor operating circuit at switch points 28 and 29, the motor turns a sufficient number of revolutions to operate through the reduction gear 34 to open the gaps a, b, c, thus stopping the motor at the desired point by breaking the circuit 31' at the gap a, between switch points 32 and 32'. The switch 33 is then in position to again energize the motor 8, when a shunt between rails 17 and 18 permits the spring 35 to draw the switch 27' into position to close the circuit 38 at the switch points 36 and 37.

The reduction gear 34 is connected to rotate the shaft 10' and swing the arms 1' and 1 into roadway clearing and closing position.

So long as the magnet 22 is energized by battery 25, the switch 27' continues to close the circuit at 28 and 29, and to break the circuit at 36 and 37, and the swinging arms 1, 1', 1'' and 1''' remain in the roadway clearing position as shown by solid lines in Fig. 1, and by dotted lines in Fig. 2. This energizing of the electro-magnet 22 continues until the rails 17 and 18 are connected by the entrance of a car C, as shown in Fig. 1, into the block A'; and thereupon the current from battery 25 is shunted through the car and the rails 17 and 18, thus de-energizing the magnet 22, and allowing the spring 35 to draw the switch 27' into position to

close the circuit between the switch point 36 of lead 30 and switch point 37 of lead 38; thereupon the motor will be driven in the direction of the feathered arrow a sufficient number of revolutions to swing the signals 70 to a road closing position and to open the gaps d, e, and f, of the switch 33, thus stopping the motor by breaking the motor operating circuit at the gap d.

A manual shunt is provided through lead 75 39, connected to rail 18, a manually operated switch 40, and the lead 41, connected to rail 17, so that when the switch 40 is closed the current from battery 25 is shunted, de-energizing the magnet 22, and allowing the 80 spring 35 to close the gap at 36 and 37, energizing the motor to operate the signal to a road closing position.

The signaling arms may or may not be provided with lamps as at 47 which may be 85 illuminated by means of a circuit 48, closed by suitable contact at 49 and 50, and connected with the power circuit which runs the motor.

The signal arms and their shafts are arranged 90 on opposite sides of the railway at a considerable distance therefrom so that when they are in signaling position, roadway passengers heedlessly approaching the railway at considerable speed will collide 95 with the warning strips far enough from the track to allow them to stop before reaching the track; and the signaling arms are of such length and their upright shafts are so near to the roadway that the arms extend 100 over the right half of the roadway at the approach toward both sides of the railway; and preferably the right side of the roadway as it leaves the railway is in like manner protected.

The arms are arranged to normally stand in road clearing position, and the mechanism above described is arranged to swing said arms from normal position against the direction of customary road travel, to close 110 the road; and with such travel to open the road; thus to quickly get out of the way of travel the moment the road is opened.

The pendant strips may be varicolored so as to be readily noticeable, thus to give 115 visual notice of the signal so as to enable road passengers to avoid colliding with the strips. Said strips, however are preferably of such material as will not injure the person colliding with them.

In operation the arms 1' and 1 will normally be in roadway clearing position because the electromagnet 22 will be energized through the connections 24, 17 and 21; 23, 18 and 17 with electrical energy from the battery 25; thereby drawing the armature 27 toward the magnet 22 and closing the switch 27', the point 28 of which is connected by lead 30 to a live wire leading to any suitable source of electrical energy H; the point 29 130

of switch 27' is connected by lead 31 to contact 32 at gap *a*. The contact 32' at gap *a* is connected by lead 31' to one terminal of the motor 8, the other terminal of which is connected by lead 51 to another live wire leading to the source of electrical energy *H*. The gap *a* is closed by switch 33 which also closes the gaps *b* and *c*, that are connected by suitable leads 52 and 53; and 54 and 55 respectively to the motor 8. The leads 53 and 54 extend to the usual armature terminals of the motor while the leads 52 and 55 extend to the field terminals thereof. The direction of the current flowing through the field and armature is reversed by the gaps *b*, *c* and *e*, *f*, as described, while gaps *a* and *d* merely act to start or stop the motor. The motor is of standard and well known construction and the electrical connections between the source of energy *H* and the field and armature windings is built into and made an inherent part of the motor at the time it is constructed. These connections are here more or less diagrammatically shown at 53^a and 54^a. The switch 33 thus closes the circuit to the motor 8 through the gaps *a*, *b* and *c* and the motor is rotated in the direction of the unfeathered arrow a sufficient number of revolutions to bring the segment 56 into position shown in full lines, Fig. 2, when the spring 56^a connected to link 56^b to which the segment 56 is connected will be to one side of the point 56', at which point the switch 33 and link 56^b are pivoted; and draw the switch 33 to the full line position when it will open the gaps *a*, *b* and *c* and close the gaps *d*, *e* and *f* and thus the current to the motor will be broken.

The arms 1' and 1 will remain in roadway clearing position until the electromagnet 22 is deenergized by shunting the current from battery 25 by closing the manually controlled switch 40 or by a car entering the insulated block A' of the railway A.

When a car C (Fig. 1) enters the insulated block A' of the railway track A the current from battery 25 is shunted from the electromagnet 22 and the spring 35 will draw the switch 27' into position shown in dotted lines, Fig. 2, and closes the circuit between the contact points 36 and 37 and between contact points 49 and 50. The contact point 36 is connected by wire 57 to the contact point 29 and thereby is connected with the source of electrical energy *H*. The contact point 37 is connected by lead 38 to contact 58 at gap *d* and switch 33 continues the circuit to contact 59 which is connected by wire 60 to contact 32' and by lead 31' to one terminal of the motor 8, the terminal of which is connected by lead 51 to the source of electrical energy *H* and thus completing the circuit.

The switch 33 in full line position, Fig. 2, also closes the gaps *e* and *f*. The contact 61

at gap *e* is connected to lead 52 and contact 62 is connected to lead 54; and the contact 63 at gap *f* is connected by wire 64 to lead 53, and contact 65 is connected by wire 66 to lead 55. The switch 33 in full line position, Fig. 2, directs the current to the motor 8 in a direction reverse to that when the switch is in dotted line position, Fig. 2, and the motor will be rotated in the direction of the feathered arrow a sufficient number of revolutions to swing the arms 1' and 1 through a quadrant and into road closing position, and to bring the segment 56 into dotted line position, Fig. 2, in which position the current to motor 8 will be broken. 80

When the armature 27 is drawn by spring 35 to close the circuit between contacts 36 and 37 the switch 27' will close the circuit between the contacts 49 and 50. The contact 50 is connected to the source of electrical energy *H* by lead 67 and the contact 49 may be connected by lead 68 to one terminal of the lamps 47 on the arms 1' and 1. The other terminal of said lamps 47 may be connected by lead 69 to the source of electrical energy *H* and thereby illuminate said lamps 47 when the circuit between contacts 36 and 37 are closed to operate the motor to swing the arms 1' and 1 into road closing position. 85

The arms 1' and 1 will be maintained in road closing position as long as the current from battens 25 is shunted by the presence of a car on the insulated block A' or by closing the switch 40. 95

I claim—

1. The combination with an electrical railway block of a reversible motor; an electric circuit to operate said motor; a horizontally swinging signal arm operable by said motor, through a quadrant; a switch to alternately connect said motor with said circuit to drive the motor first in one direction and then in the other; yielding means to hold said switch in position to cause the motor to move the arm in signaling position to intercept travel; an electro-magnet energized by the current in the block when the track is clear to hold the switch in position to connect the motor with the circuit to swing the arm out of travel intercepting position, and a double throw switch operable by the motor to stop the motor at the end of a quadrant movement of the arm and to come into position to reverse the motor when the change from clear track to closed track is made, and to again reverse the motor when the change from closed track to clear track is made. 100

2. In a railway and roadway crossing signal apparatus; an insulated railway block and electrical source of supply connected to said block; a solenoid connected to said block and adapted to be energized by said electrical source; signal arms; a motor adapted to operate said signal arms and an electrical circuit connected to said motor; a switch in 105

said circuit adapted to be operated by said solenoid; another switch in said circuit operable by said motor to break the circuit to said motor after said signal arms have been moved a predetermined distance; and means operable by said first mentioned switch when said electromagnet is deenergized by shunting the electricity from said electrical source to close the circuit to said motor to move 10 said arms, said first mentioned switch being adapted to be moved by energizing said electromagnet when the shunting of the electrical energizer has been discontinued to close the circuit to said motor in a reverse 15 direction to move the signal arms in a reverse direction to starting position.

3. In a railway and roadway crossing signal apparatus; an insulated railway block; signal arms; a motor connected to operate 20 said arms and an electrical circuit to said motor; a switch in said circuit adapted to be controlled by a car entering said insulated block; a pivotally mounted switch operable by said motor to break the circuit to 25 said motor after said signal arms have been moved a predetermined distance, a segment oscillatable by said motor and a pivotally mounted link connected to said segment and yielding means connecting said link and said 30 switch to operate said switch when the segment has been moved a predetermined distance so as to bring the yielding means to one side of the pivoted connection.

4. In a railway and roadway crossing signal apparatus; an insulated railway block; signal arms normally in roadway clearing 25 position; a motor to operate said arms; an

electrical circuit connected to said motor; a switch operable by said motor adapted to break the circuit to said motor when said 40 arms have been moved a predetermined distance and to direct the electrical circuit to said motor in a reverse direction; another switch and means controlled by a car entering said insulated block to move said other 45 switch to close the circuit to said motor to move said arms into roadway closing position, and to again operate said other switch after the insulated block has been cleared of cars to again close the circuit to said motor 50 to move the arms into roadway clearing position.

5. In a railway and roadway crossing signal apparatus; an insulated railway block; signal arms; a motor connected to operate 55 said arms and an electrical circuit to said motor; a switch in said circuit adapted to be controlled by a car entering said insulated block; a pivotally mounted switch operable by said motor to break the circuit to said 60 motor after said signal arms have been moved a predetermined distance, a segment geared to said motor and oscillated thereby, a pivotally mounted link connected to segment, a spring secured to said link and said 65 switch to operate said switch when the segment has been moved a predetermined distance so as to bring the spring to one side of the pivot point of said link.

In testimony whereof, I have hereunto 70 set my hand at Los Angeles, California, this 4th day of May, 1922.

FRED VAN WAY.
